UNITED STATES PATENT OFFICE.

WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT DETECTOR FOR BOX LOOMS.

Application filed January 2, 1925. Serial No. 26.

This invention relates to improvements in weft detectors for box looms such as are employed in weaving fabrics having relatively coarse and fine weft. In my co-pending 5 application, Serial No. 757,234 there is shown a feeler having a detecting surface adjustable under control of the active shuttle, the detector becoming more sensitive when cooperating with fine yarn and becoming 10 less sensitive when cooperating with coarse yarn. The invention disclosed herein relates to a detector having a yarn penetrating member and a laterally swinging member so arranged that the penetrating 15 member is movable in timed relation with the active shuttle.

It is the general object of my invention to provide means for positively moving the detector from one position to another by 20 means of connections controlled by the color slide of the usual multi-color weft replenishing mechanism, more particularly a replenishing mechanism to supply two colors.

It is a further object of my invention to 25 provide means for initiating the movement of the detector from one setting to the other and to provide additional means for completing the movement, the setting of the detector being maintained for all movements 30 thereof in the direction in which the lay travels.

With these and other objects in view which will appear as the description proceeds, my invention resides in the combination 35 and arrangement of parts hereinafter described and set forth in the claims.

In the accompanying drawings wherein I have shown a convenient form of my invention,

Fig. 1 shows a portion of a multi-color replenishing mechanism with my improved detector associated therewith as viewed from the central portions of the loom,

Fig. 2 is a front elevation of the structure shown in Fig. 1 looking in the direction of arrow 2, Fig. 1,

Fig. 3 is a horizontal section on line 3—3 of Fig. 2,

Fig. 4 is a vertical section on line 4—4 of Fig. 3 looking in the direction of the arrows,

Fig. 5 is an enlarged vertical section on line 5—5 of Fig. 4,

Fig. 6 is an enlarged vertical section on line 6—6 of Fig. 3, and

Fig. 7 is a fragmentary view showing the 55 relation of the swinging and penetrating detectors in the positions they assume when cooperating with coarse yarn.

Referring to the drawings it will be seen that I have shown the invention as applied to a weft detector having a yarn penetrating member and a laterally swinging member associated therewith having a roughened yarn engaging surface which is restrained against movement by the presence of sufficient 60 yarn but is free to turn when the yarn becomes depleted to such an extent as to render desirable the indication of weft exhaustion. A loom frame 10 has secured thereto inner plate 11 of a multi-color weft 65 replenishing mechanism. Said mechanism has the usual transerrer 12 above which is mounted a color indicating slide 13 on which is mounted a pair of fingers 14 one of which is indicated in Fig. 1. Said slide 13 is 70 mounted for both longitudinal and angular motion, being oscillated in bearings 15 formed on the plate 11 and being movable longitudinally in said bearings by mechanism under control of the shifting shuttle 75 boxes. This mechanism is not shown in the drawings but is substantially the same as that set forth in Patent No. 1,030,748 to Ryon. For the purposes of the present invention it is sufficient to state that said slide 80 13 moves longitudinally in timed relation with the active shuttle.

The weft detector is mounted on a support 16 from which projects upwardly an arm 17 through which extends a controller 18 clearly shown in Fig. 3. The controller 18 is normally to one side of the slot 19 to permit lever 20 to move downwardly at regular intervals without being obstructed. Whenever the controller 18 extends under the lever 20 95 the latter will be effective to indicate weft exhaustion as set forth in the aforesaid patent.

The support 16 has projecting therefrom a stud 21 on which is mounted a threaded 100 sleeve 22 passing through a hub 23 depending from the feeler bed 24. Said bed has slidably mounted therein a rectangular tubular case or slide 25 from which depends a clip 26 having extending therethrough the 105 reduced end of a stud 27. The rear end of said stud is enlarged and threaded as at 28 to pass through the bed 24 and limit rear-

ward movement of the slide 25 and clip 26 as the latter are moved under influence of spring 29 which surrounds said stud 27 and pushes against the forward end of the bed 24. The bed is provided with a cap 30 which is secured thereto as by screws 31 to prevent upward movement of the slide 25.

Pivottally mounted on the slide 25 as at 32 is a detector member 33 the rear end of 10 which is provided with a roughened surface 34 and the forward end of which is formed as a finger 35. Said swinging detector is provided with a surface 36 to engage a stop screw 37 adjustably threaded through the 15 cap or cover 30 as shown in Fig. 6. Said stop screw is to one side of the pivot 32 and as the slide 25 is moved rearwardly under action of spring 29 said stop screw will engage the surface 36 to give the detector 33 20 a movement to the right holding said detector 33 as viewed in Fig. 3.

Pivoted as at 38 to the forward end of the casing 25 is a lever 39 having a rearwardly extending arm 40 engaging finger 35 of the 25 swinging detector and connected to the controller 18 as at 41. A pin 42 projects laterally from the lever 39 and has located therein a compression spring 43 one end of which presses against said lever 39 and the other 30 end of which presses against an extension 44 projecting forwardly from the slide 25.

When the parts are in the position shown in Fig. 3 the slide 25 is held in rear position with the detector 33 held against the yarn 35 penetrating member 50 to be described hereinafter but with the spring 43 acting normally to move said detector to the left because of the connection between the finger 35 and arm 40. When sufficient yarn 40 for continued weaving is present said detector 33 will be restrained against angular motion with respect to the slide 25 and the controller 18 will be moved forwardly but when insufficient yarn is present said detector 33 is given a left hand movement by 45 the spring 43 to move the controller 18 under the lever 20 to indicate weft exhaustion as previously described. The matter thus far described is similar to well known construction 50 and forms no part of my invention.

My present invention relates more particularly to the means for controlling the position of the second detector 50 which is slidably mounted in the case or slide 25 to the 55 end that the length of waste remaining at indication of exhaustion will be substantially the same for coarse and fine yarn. The type of feeler illustrated herein is of the general form shown in Patent No. 972,722 60 and depends for its operation on the fact that the rear end of the yarn penetrating detector 50 lies behind the roughened surface 34, the difference between the positions of the rear portions of each of the detectors 65 measuring the amount of yarn remaining on

a bobbin when indication of weft exhaustion is given. As any predetermined length of waste of fine yarn remaining at the time of indication of weft exhaustion will represent a smaller layer of yarn on the bobbin than 70 would be the case with coarser yarn, it is desirable that the detector 50 be given different positions so as to provide for substantially the same yarn wastage as regards length. In carrying out my invention I 75 mount an eccentric 51 on a stud 52 which is riveted or otherwise secured to the slide 25 as shown in Figs. 3 and 6. A cap screw 53 threaded into the stud 52 prevents upward movement of the eccentric 51. An arm 54, 80 shown in Figs. 3 and 5, projects laterally from the stud 52 and is rigid with the eccentric 51. Projecting upwardly from the sliding detector 50 is a pin 55 to which is connected the rear end of a tension spring 56 the forward end of which is connected to a pin 57 projecting upwardly from the arm 54.

In order to move the eccentric 51 there is provided a control lever 58 having a pair of 90 guide surfaces 59 and 60, respectively, against one of which the pin 57 will normally rest under action of the spring 56. Said control lever 58 is pivoted as at 61 to the cap 30 and has a laterally projecting arm 62 having a slot 62' therein by means of which link 62^a may be adjustably connected therewith. The forward end of said link carries the rod head 63 which is adjustably connected to a lever 64 by means of stud 65 which projects through slot 66 in said lever 64. Said lever 64 is adjustably secured to the lower end of an upright shaft 67 rotatably mounted in bearings 68 associated with the plate 11 of the replenishing mechanism. Adjustable collars 69 and 70 secured on the shaft 67 engage opposite sides of one of the bearings 68 to limit vertical motion thereof. Projecting forwardly from the shaft 67 and 100 adjustably secured thereto is an upper arm 71 having a finger 72 which extends into a slot 73 formed in a collar 74 adjustably secured to the outer end of the color slide 13.

As shown in Fig. 3 the detector is set for 110 cooperation with fine yarn, the spring 56 holding the forward end of the detector 50 against the low part of the eccentric 51 and also holding the pin 57 against surface 59 of lever 58. Said lever 58 is so disposed that the surface 59 is parallel to the motion given the slide 25 by the advancing lay when the parts are in the position shown in Fig. 3. The setting of the detector is shown in Fig. 3 to correspond to the forward position of the collar 74 on the color slide but as previously described when the active shuttle changes and the coarse yarn becomes active the slide 13 will be moved rearwardly, or to the left as seen in Fig. 1, thus moving the collar 74 to the dotted line position. This 115 120 125 130

produces a right hand rotation in the upright shaft 67 as viewed in Fig. 3 and through intermediate connections the lever 58 will move to the left, the pin 57 being moved to the left by the surface 59 until the spring 56 passes over the stud 52 at which time said spring will move the pin 57 against guide surface 60. When lever 58 is thrown to the left the guide surface 60 will be parallel to the movement given the slide 25 by the lay. By reason of the disposition of the surfaces 59 and 60 the setting of the eccentric 51 will not be altered by the longitudinal movement of the detector slide 25.

15 A lug 75 carried by the penetrating detector 50 extends upwardly through a slot 76 and slot 77 formed in the cap 38 and the casing 25, respectively.

When the lever 58 is moved as described 20 the large part of the eccentric is turned toward the detector 50 moving the latter rearwardly against the action of spring 56 so that the detecting elements assume the relative position shown in Fig. 7. In this position it will be understood that a greater depth of waste remains on the bobbin at the time of indication of exhaustion which is necessary when detecting with coarse yarn.

From the foregoing it will be seen that I 30 have provided a weft detector having a penetrating element and a swinging element wherein the relative positions of said elements are changed to render the detecting surfaces more or less sensitive according to 35 the character of yarn being woven and that the motion for effecting the relative change is communicated positively from the color slide of the usual multi-color weft replenishing mechanism. Furthermore it will be 40 noted that the lever 58 initiates the movement of the eccentric and that the spring 56 completes the movement. Also, the guide surfaces 59 and 60 are so disposed that the one which engages pin 57 will be parallel to 45 the slide 25 so as not to alter the setting of the eccentric as the slide moves forwardly.

Having thus described my invention it will be apparent that changes and modifications 50 may be made therein by those skilled in the art without departing from the spirit and scope of the invention and I do not wish to be limited to the details herein disclosed, but what I claim is:

1. In a weft replenishing loom having a 55 plurality of shifting shuttle boxes and a member movable in timed relation with the shuttle boxes and dependent for its position upon which shuttle box is in active position, a weft detector having a detector surface 60 movable to assume various adjusted positions, means interposed between the member and the detector to initiate a change in the adjustment of said detector as said member moves upon a shifting of the shuttle boxes 65 to bring a new shuttle box into active posi-

tion, and additional means to complete the motion to change the adjustment of said detector.

2. In a multi-color weft replenishing mechanism for a loom having shifting shuttle boxes and a color slide moving in timed relation with the shuttle boxes of the loom, two detectors capable of assuming varying relative positions, an eccentric operatively connected with one of said detectors, and a 70 connection between the color slide and the eccentric to move said eccentric and detector operatively connected therewith in timed relation with the color slide and relatively to the other detector. 75

3. A multi-color weft replenishing mechanism for a loom having a plurality of shifting shuttle boxes and a member movable in timed relation with the shuttle boxes of the loom, a pair of relatively adjustable detectors one of which is movable with respect to the other to indicate substantial weft exhaustion, and means including an eccentric interposed between the member and the other detector to vary the relative adjustment of said detectors. 80

4. In a weft replenishing loom having a plurality of shuttle boxes, weft replenishing mechanism having a color slide to move in timed relation with the shuttle boxes, a weft 90 detector having a yarn penetrating member and a pivotally mounted yarn impinging member, and means including an eccentric interposed between the color slide and one of said detectors to cause relative movement 95 of said members to render said detector more or less sensitive depending upon which shuttle box is in active position. 100

5. In a loom, multi-color weft replenishing mechanism including a color slide, a weft 105 detector having a sliding element, a yarn impinging detector member pivotally mounted on said sliding element, a yarn penetrating member slidably mounted on said sliding element, and rotary means operatively connected with the color slide and engaging one of said members to vary the relative position of said pivoted yarn impinging member and said yarn penetrating member. 110

6. In a loom, multi-color weft replenishing mechanism including a color slide, a weft 115 detector, an element for said detector slideable under influence of the lay, a yarn impinging member pivotally mounted on said element, a yarn penetrating member slidably mounted on said element, a lever mounted on a fixed center, connections between the color slide and said lever to move the latter when the color slide moves, and an eccentric controlled by the lever and operatively connected to the yarn penetrating member to cause relative longitudinal movement between the members when said lever is moved by the color slide. 120

7. In a loom having a plurality of shifting 125

shuttle boxes, a multi-color weft replenishing mechanism having a device movable in timed relation with the shuttle boxes, a weft detector, a slidably mounted element forming part of said detector and movable under influence of the lay, a yarn impinging member pivotally mounted on the element, a yarn penetrating member slidably mounted on said element, a lever movable in timed relation with the device, an eccentric operatively connected to one of said detectors, and actu-

ating connections between the lever and said eccentric to move said eccentric whenever said lever is moved, said connections including guiding surfaces operative one at a time ¹⁵ to actuate said eccentric, each of said guide surfaces when in position to actuate said eccentric being substantially parallel to the direction in which the element moves.

In testimony whereof I have hereunto ²⁰ affixed my signature.

WALTER H. WAKEFIELD.
